CLAIM

The ornamental design for a pet treat, as shown and described.

DESCRIPTION

FIG. 1 is a perspective view of a pet treat showing our new design; the broken lines and the area surrounded by said broken lines form no part of the claimed design;

FIG. 2 is a front view of the design shown in FIG. 1; the broken lines define the bounds of the claimed design; the broken lines themselves forming no part of the claimed design;

FIG. 3 is a back view of the design shown in FIG. 1; the broken lines define the bounds of the claimed design; the broken lines themselves forming no part of the claimed design;

FIG. 4 is a left view of the design shown in FIG. 1; the broken lines define the bounds of the claimed design; the broken lines themselves forming no part of the claimed design;

FIG. 5 is a right view of the design shown in FIG. 1; the broken lines define the bounds of the claimed design; the broken lines themselves forming no part of the claimed design;

FIG. 6 is a top view of the design shown in FIG. 1; the broken lines and the area surrounded by said broken lines form no part of the claimed design; and,

FIG. 7 is bottom view of the design shown in FIG. 1; the broken lines and the area surrounded by said broken lines form no part of the claimed design.
